Primary Examiner — Karen S Acker*Assistant Examiner* — Wendy Arminio(74) *Attorney, Agent, or Firm* — Dorsey & Whitney LLP**CLAIM**

The ornamental design for a cellular shade component, as shown and described.

DESCRIPTION

FIG. 1 is an isometric view of the front and left sides of a cellular shade component;

FIG. 2 is a left side elevation view of FIG. 1;

FIG. 3 is a front elevation view of FIG. 1. The rear elevation view is a mirror image thereof; and,

FIG. 4 is a top plan view of FIG. 1. The bottom plan view is a mirror image thereof.

The dot-dash-dot broken lines as shown in FIGS. 1 and 4 represent the boundaries of the claim and form no part thereof. The dash-dot broken lines in FIGS. 1-4 represent portions of the cellular shade component that form no part of the claimed design.
